United States Patent Office.

JOHN H. HIGGINS, OF NEW YORK, N. Y.

Letters Patent No. 99,189, dated January 25, 1870.

IMPROVEMENT IN APPARATUS FOR STEAMING YARN.

The Schedule referred to in these Letters Patent and making part of the same.

To all whom it may concern:

Be it known that I, JOHN H. HIGGINS, of the city, county, and State of New York, have invented a new and useful Improvement in Apparatus for Steaming Yarns and other fibrous material, of which the following is a full, clear, and exact description, reference being had to the accompanying drawing, forming part of this specification, and in which—

Figure 1 represents a side elevation of a carriage or frame, constituting my improved apparatus, and

Figure 2, a plan of the same.

Figure 3, an end view, and

Figure 4, a central transverse section thereof.

Figure 5 is a plan of a skeleton frame for holding the yarns or material to be treated.

Similar letters of reference indicate corresponding parts.

My improvement is more especially designed to be applied to the steaming of printed or variously-colored yarns or warps, as used in the manufacture of carpets, and will here be described in such connection; and

The invention consists in a novel construction of apparatus involving a new or different mode of procedure or process for accomplishing such work, whereby the same is effected more expeditiously and perfectly, and the use of straw or rice-hulls, as covering-material for the yarns while being steamed, is dispensed with.

In fixing the colors of such yarns by steaming, it has been customary to place the yarns, in hanks or otherwise, in wooden boxes, the bottoms of which were formed with openings at intervals, for the steam to reach the yarns, which were covered with cut straw or rice-hulls, to absorb the surplus color, and prevent staining or damage of the yarns by running of the colors or dripping from the one box to the other, the boxes being piled one upon or over the other, on a frame or carriage, for running them into the steaming-box or chamber.

Such forms a slow and defective process, and very imperfectly exposes the yarns to the action of the steam, while it is expensive and otherwise objectionable, by reason of the quantity of straw or rice-hulls required to cover the yarns, and the frequent necessary renewal of such covering.

Under my improvement, I employ a frame, constructed substantially as shown in the accompanying drawing, in which—

A is the carriage-portion of the frame, provided with flanged wheels a, for travel on suitable rails, to facilitate transportation to and from the steam-box.

On this carriage is erected a structure which embraces end-portions or frame-sections, B B, formed of a vertical standard, and branches or arms b b, arranged in pairs or sets, one above the other, and lying or running in opposite directions toward the sides of the apparatus.

These arms b b are formed to incline upward, in an outwardly direction, on their under side, to correspond with the dip of dripping-plates or trays C C, lying between the end-frames B B, and which incline downward from opposite sides toward a centre clearance or space, c, but which may incline in reverse directions, and the arms b b be otherwise shaped or constructed, to receive through them stretching-screws e e, jointed or otherwise secured to the ends of the trays, and operated by nuts d d on the outside of the arms b b.

Said trays C C may be made of zinc or other suitable metal or material, and are supported between the end-sections B B, by passing over and resting on rods f f, arranged below the bottom edges of arms b b, of intermediate sections B' B', of similar construction to the sections or portions B B of the frame, and united therewith by brace or tie-rods g g.

The yarns to be steamed are carried, in hanks, by loose and independent skeleton frames D, of a suitable length and size to lie upon the arms b and b', above the dripping-plates or trays on each side of the central standards of the main frame.

These yarn-carrying frames D are made up of a network of twine extending over their entire surface, so that the yarns lying on said nets are fully and freely exposed to the action of the steam.

In this way, or by this improvement, the yarns may be steamed more expeditiously and perfectly; there is no danger of staining or injuring them; the drip or waste is prevented by the trays from running from box or frame to frame, carrying the yarns, and is conveyed away to a point or line of delivery out of reach of the yarn-holding frames, and the necessity for cut straw or rice-hulls, as a covering to the yarns, is altogether dispensed with.

What is here claimed, and desired to be secured by Letters Patent, is—

1. The combination of a steaming-frame or structure, made up of or carrying a series of inclined dripping-plates or trays, arranged, the one above the other, and net or open-work yarn-carrying frames, substantially as and for the purpose or purposes specified.

2. The combination, in the one apparatus, of a lower carriage-portion or wheel-base, A, the main frame or frame-sections B B', with their arms or branches b b', and the inclined dripping-plates or trays C, essentially as shown and described.

3. The dripping-plates or trays C, provided with stretching or straining-screws e, and nuts d at their ends, in combination with the frame-sections B B, and intermediate carrying-rods or supports f f, substantially as described.

JOHN H. HIGGINS.
